CLAIM

The ornamental design for a float device having propelling device, as shown and described.

DESCRIPTION

FIG. 1 is a right upper perspective view of a float device having propelling device showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof.

FIG. 8 is a left upper perspective view thereof.

FIG. 9 is a right bottom perspective view thereof.

FIG. 10 is a left bottom perspective view thereof.

FIG. 11 is an exploded view thereof; and,

FIG. 12 is a right and exploded view thereof.

The evenly-spaced broken lines immediately adjacent claimed surfaces represent boundaries that form no part of the claimed design; all other evenly-spaced broken lines represent unclaimed environmental subject matter and form no part of the claim. The dash-dot broken lines is for illustrative purposes only.

1 Claim, 10 Drawing Sheets
